UNITED STATES PATENT OFFICE.

PHILIP H. NOLTING, OF JERSEY CITY, NEW JERSEY.

WATCH GUARD.

Application filed February 10, 1922. Serial No. 535,641.

To all whom it may concern:

Be it known that I, PHILIP H. NOLTING, a citizen of the United States, and a resident of Jersey City, in the county of Hudson and State of New Jersey, have invented a new and Improved Watch Guard, of which the following is a full, clear, and exact description.

This invention relates to improvements in watch guards, an object of the invention being to provide a guard for watches which is equipped with a novel means for preventing the accidental loss of a watch from a pocket.

15 A further object is to provide a guard of this character, which can be readily sewed into a pocket, and which will be simple and practical in construction, strong, durable and efficient in use, and comparatively inexpensive to manufacture.

20 Many guards of this character have been previously invented, but they have all proven either impractical in construction, or have had a damaging effect upon the clothing of the wearer. My improved device overcomes these difficulties.

25 With the above enumerated and other objects in view, the invention consists in certain novel features of construction, and combinations and arrangements of parts as will be more fully hereinafter described and pointed out in the claims.

In the accompanying drawings:

30 Figure 1 is a view in side elevation of a watch secured in my improved protector or guard;

Figure 2 is a sectional view through a watch pocket, showing my improved watch guard in place and in use; and

40 Figure 3 is a perspective view of the spring which is used in the guard.

Referring in detail to the drawings, I have used the reference numeral 1 to designate a garment provided with a pocket 2 therein. In carrying out the invention, my improved watch guard or protector, designated by the reference numeral 3 is preferably sewed or otherwise secured at its intermediate portion to the bottom of the

50 pocket. This protector which may be formed either from a single length of wire covered with leather, or by an arcuate flat spring is substantially U shaped, as seen most clearly in Figure 1. The extremities of the U,

however, extend inwardly exerting a clamp- 55 ing action upon a circular body and causing the protector to embrace the same.

In the particular embodiment of the invention herein shown, I have used a spring which comprises a single length of wire 4 60 bent to provide a double spring of arcuate form. The intermediate portion 5 of the wire forms one end of the arc or U shaped body and a covering of leather conceals the wire. The free ends of the wire are flared 65 slightly apart adjacent their extremities, as indicated at 6, and the leather casing or covering for the wire is bifurcated or split adjacent the ends of these arms, as seen most clearly at 7 in Figure 2.

70 This construction provides a pair of leather covered spring arms adapted to embrace the stem of a watch 8. After the guard or protector has been sewed into the pocket, as indicated at 9 in Figure 2, the 75 insertion of a watch into the pocket will spread the arms of the U shaped protector apart, and as the watch is further forced into place, they will exert a clamping action on the watch. At the same time the other 80 arms at opposite sides of the bifurcated portion 7 will receive the stem of the watch and positively hold the same against accidental withdrawal from the pocket.

85 It will be obvious that the construction of the guard or protector might be infinitely varied and that the exact material from which the guard is made does not necessarily form any part of this invention, since other guards of substantially U shape with bifurcated ends would serve the same purpose.

90 Although I have illustrated the preferred embodiment of my invention, it will be apparent that various slight changes and alterations might be made in the general form 95 and arrangement of the parts described without departing from the invention, and hence I do not wish to limit myself to the precise details set forth, but shall consider myself at liberty to make such slight changes 100 and alterations as fairly fall within the spirit and scope of the appended claims.

I claim:

1. The combination with a pocket, of an arcuate spring watch guard secured at its intermediate portion to the bottom of the pocket, and adapted to embrace a watch in the pocket, said guard being bifurcated at

one end to receive the stem of a watch in the pocket.

2. In a watch guard, an arcuate spring body shaped to receive a watch, said arcuate spring body being bifurcated at one end to receive a watch stem, and a casing stretched over the spring body.

3. In a watch guard of the character described, an arcuate spring body portion shaped to receive a watch, said spring body portion being bifurcated at one end, the prongs of said bifurcated end being curved to receive and grip the watch stem.

PHILIP H. NOLTING.
